PRODUCTION OF HYDROGENATION DERIVATIVES OF DYPNONE

Ernest Joseph Lush, Wimbledon, London, England, assignor to A. Boake Roberts and Company Limited, London, England, a British company

No Drawing. Application May 10, 1948, Serial No. 26,247. In Great Britain May 15, 1947.

11 Claims. (Cl. 260—590)

1

This invention relates to a process whereby hydrogenation derivatives of dypnone, i. e. dihydrodypnone and dihydroydypnol, may be produced direct from acetophenone on a commercial scale, thus making available products which have been found to have outstanding properties as plasticisers and for other purposes.

It has been proposed hitherto to heat acetophenone with hydrogen iodide and phosphorus at 130—150° C. (Graebe, B, volume 7, page 1625), and this treatment brought about the formation of hydrogenated dypnone, but obviously such a process is not a commercial proposition.

It has also been proposed (see "Reactions of Hydrogen" by Homer Adkins, 1937, page 50) to hydrogenate acetophenone with the aid of a nickel catalyst at temperatures of 110—150° C. under pressure, and under these conditions phenyl methyl carbinol has been produced.

It is also known that at a somewhat higher temperature (175° C.) ethyl benzene is formed at a commercial rate of formation and it was a natural assumption to make that any attempt to form dihydrodypnone by direct hydrogenation of acetophenone would lead either to the formation of the carbinol or ethyl benzene or mixtures of the two.

The surprising discovery has now been made, however, that at a still higher temperature range than that most favourable to the formation of ethyl benzene, and in the actual trials made using a rapid current of hydrogen at atmospheric pressure and a nickel catalyst, acetophenone may be hydrogenated with the formation of only negligible amounts of phenyl methyl carbinol and ethyl benzene, but with the formation of dihydrodypnone in almost quantitative yields. The rate of formation of dihydrodypnone commences to be appreciable under the above conditions at 160° C. and assumes commercial proportions between 180° C. and the decomposition point at 250° C. It will be appreciated that the actual temperature ranges given in the three cases cited above will depend upon the catalyst chosen.

It has further been found that when the conversion of acetophenone to dihydrodypnone has reached a maximum, if the temperature be lowered to 70 to 100° C. and the hydrogenation continued, other things remaining the same, the dihydrodypnone is converted into dihydroydypnol. The above reactions may be represented as follows:

2

The invention appears to depend upon the production of dypnone and its practically simultaneous hydrogenation before any appreciable polymerisation can take place, the hydrogenated product being stable. It was found that if acetophenone is heated in the presence of a nickel catalyst without hydrogen, condensation of two molecules of acetophenone takes place with the formation of commercial yields of dypnone. It was found, however, that under the most favourable conditions considerable polymerisation of the dypnone occurred and in practice as much as 12% of dihydroydypnol and resin was obtained.

The invention is not based on any theory of what actually occurs during the reaction but is based on the discovery that if acetophenone is heated under conditions which are conducive to condensation with the continuous removal of the water formed thus effecting the formation of dypnone and sufficient hydrogen is introduced to reduce dypnone as fast as it is formed to dihydrodypnone, then the latter will be produced in almost quantitative yields.

According to the present invention, therefore, a process for the production of hydrogenation derivatives of dypnone from acetophenone comprises the step of heating the acetophenone at a temperature of 160 to 250° C. in the presence of a catalyst as hereinafter specified, and introducing hydrogen at a sufficient partial pressure to convert dypnone to dihydrodypnone as fast as it is formed.

Suitable catalysts are nickel and copper or compounds of these metals which will be easily converted to the metal on heating; a suitable catalyst may be produced by the decomposition of nickel formate in a high boiling sulphur-free hydrocarbon. Other known catalysts capable of promoting the above condensation of a ketone may be used provided the catalyst chosen will promote the hydrogenation of dypnone as it is formed.

It is believed that the freedom of the reaction products from dypnone polymerisation products is dependent upon the successful synchronisation of the rate of dypnone formation with the rate of hydrogenation so that dypnone does not accumulate in the products of reaction, otherwise resin is formed. One convenient way in which this essential synchronisation may be effectively maintained is by conducting the hydrogenation in a rapid current of hydrogen at atmospheric pressure commencing the reaction at a temperature considerably above the temperature at which phenyl methyl carbinol is principally

formed but below that most suitable for dypnone condensation. Thus, a suitable commencing temperature is 180-190° C. The temperature may be raised later to about 250° C.

The dihydrodypnone may be isolated from the reaction products and used as such by removing the small amount of unchanged acetophenone, e. g. by steam distillation. Alternatively, as indicated above, the dihydrodypnone may be further hydrogenated without previous isolation simply by reducing the temperature to 70 to 100° C. when the conversion of acetophenone to dihydrodypnone has reached a maximum, the process being otherwise continued but preferably with mechanical agitation.

On the other hand, the dihydrodypnone may be isolated and submitted to hydrogenation in a separate operation at superatmospheric pressure at a temperature of 70 to 100° C. or by the ketone reduction of dihydrodypnone in the presence of an alcohol such as isopropyl alcohol and an aluminium alkoxide such as aluminium isopropoxide until no more acetone is formed.

Where for any reason the presence of polymerisation products of dypnone is not a disadvantage, it is quite feasible from a commercial point of view to condense acetophenone to dypnone using nickel as condensing agent, and subsequently to reduce it by other chemical means, in particular by hydrogenation. The dypnone obtained in this way, however, has been found to be associated with 12% of didypnone and resin. The following examples illustrate the production of dihydrodypnone and its further hydrogenation to dihydrodypnol.

Example I

500 grams of acetophenone were heated in the presence of 40 grams of nickel catalyst in a rapid current of hydrogen to a temperature of 180-190° C. for 8½ hours. The water was removed through an air condenser in the form of steam in a current of hydrogen and condensed. A product was obtained having a melting point of 32-34° C.; this product had the following composition:

	Per cent
Unchanged acetophenone	12
Dihydrodypnone	80
Dypnone	6
Resin	2

The unchanged acetophenone was removed by steam distillation and was found to contain 10% of phenyl methyl carbinol and 2-5% ethyl benzene.

As the unchanged acetophenone and also the dypnone can be recycled in the process, it will be seen from the above figures that the actual yield of dihydrodypnone is something of the order of 90%. The important feature about the above figures is the small production of resin.

Example II

10 lbs. of acetophenone and ½ lb. nickel catalyst were heated in an autoclave supplied with a mechanical stirrer to 180° C., a current of hydrogen being passed through very slowly at first the rate being increased when the temperature reached 180° C. After nearly 0.75 lb. of water had been collected from the condenser attached to the autoclave the temperature was lowered to 70° C. and the hydrogen current continued until samples from the autoclave no longer crystallised at low temperatures. The contents of the autoclave were found to consist

mostly of dihydrodypnol (1 hydroxy 1,3 diphenyl butane). Any unchanged acetophenone can be removed before cooling to 70° C. or removed after hydrogenation as phenyl methyl carbinol. From the original 10 lbs. acetophenone about 8½ lbs. of dihydrodypnol were produced.

Example III

10 lbs. of dihydrodypnone and ½ lb. nickel catalyst were charged to a closed autoclave and heated to 70° C. with mechanical agitation in a hydrogen atmosphere raised to a pressure of 100 lbs. Hydrogen was rapidly absorbed and about 9 lbs. of dihydrodypnol were obtained. Some diphenyl butane was produced, about 5% at 70° C. and about 15% at 100° C., the exact amount varying with the activity of the nickel catalyst.

Example IV

Dihydrodypnone can be hydrogenated to dihydrodypnol by other methods commonly employed in the hydrogenation of ketones.

Thus, 10 lbs. of dihydrodypnone were charged to a still fitted with a reflux condenser and overflow condenser. 4 lbs. of isopropyl alcohol and 25 4 ozs. of aluminium isopropoxide were added and the whole heated to boiling point. From the top of the reflux condenser acetone was obtained and when no more acetone could be obtained the contents of the still were found to consist essentially of dihydrodypnol. No diphenyl butane could be detected in this method of hydrogenation.

Dihydrodypnone is a crystalline solid with a melting point of 72° C. and a boiling point of 170° C. at 2 mm. pressure. It is practically insoluble in water but soluble in most organic solvents, from which it is readily crystallised. It is stable to heat, light and water, and unlike esters which are used extensively as plasticisers, it is not attacked by hydrolysing agents such as water 40 and dilute alkalies. It is compatible with polyvinyl chloride up to 30%, polystyrene up to more than 20%, and cellulose acetate up to 10%, and polyvinyl acetate up to 10%. It is more insoluble in water and more stable than dimethyl phthalate 45 while having adequate light and heat stability and low volatility. It is also capable of being used in association with other plasticisers which confer special properties such as the non-inflammable properties conferred by tricresyl phosphate. Dihydrodypnol, while having similarly 50 advantageous properties as a plasticiser, has the further advantage of being liquid at atmospheric temperatures so that for certain purposes it has advantages over the dihydrodypnone.

55 I claim:

1. A process for the production of hydrogenation derivatives of dypnone from acetophenone which comprises heating the acetophenone at a temperature of 180 to 190° C. in the presence of a 60 finely divided nickel catalyst in a rapid current of hydrogen at atmospheric pressure, and finally raising the temperature to about 250° C.

2. A process for the production of hydrogenation derivatives of dypnone from acetophenone which comprises heating the acetophenone at a 65 temperature of 180 to 190° C. in the presence of a finely divided nickel catalyst in a rapid current of hydrogen at atmospheric pressure, finally raising the temperature to about 250° C., and isolating dihydrodypnone from the reaction products.

3. A process for the production of hydrogenation derivatives of dypnone from acetophenone which comprises heating the acetophenone at a 70 temperature of 180 to 190° C. in the presence of a finely divided nickel catalyst in a rapid current of

hydrogen at atmospheric pressure, raising the temperature to about 250° C., and when the formation of dihydrodypnone has reached a maximum, reducing the temperature to 70 to 100° C., continuing the introduction of hydrogen, and isolating dihydrodypnol from the reaction products.

4. A process for the production of hydrogenation derivatives of dypnone from acetophenone which comprises the step of heating at approximately atmospheric pressure the acetophenone at a temperature of 160 to 250° C. in the presence of a finely-divided nickel catalyst, introducing excess hydrogen and removing water vapor from the reaction vessel as fast as it is formed.

5. A process for the production of hydrogenation derivatives of dypnone from acetophenone which comprises the step of heating at approximately atmospheric pressure the acetophenone at a temperature of 160 to 250° C. in the presence of a finely-divided nickel catalyst, introducing hydrogen in sufficient excess to remove water vapor from the reaction vessel as fast as it is formed.

6. A process for the production of hydrogenation derivatives of dypnone from acetophenone which comprises the step of heating at approximately atmospheric pressure the acetophenone at a temperature of 160 to 250° C. in the presence of a finely-divided nickel catalyst, introducing hydrogen in sufficient excess to remove water vapor from the reaction vessel as fast as it is formed, and isolating dihydrodypnone from the reaction products.

7. A process for the production of hydrogenation derivatives of dypnone from acetophenone which comprises heating at approximately atmospheric pressure the acetophenone at a temperature of 160 to 250° C. in the presence of a finely-divided nickel catalyst, introducing excess hydrogen, removing water vapor from the reaction vessel as fast as it is formed, and when the formation of dihydrodypnone has reached a maximum, reducing the temperature to 70 to 100° C., continuing the introduction of hydrogen, and isolating dihydrodypnol from the reaction products.

8. A process for the production of hydrogenation derivatives of dypnone from acetophenone which comprises heating at approximately atmospheric pressure the acetophenone at a temperature of 160 to 250° C. in the presence of a finely-divided nickel catalyst, introducing hydrogen in sufficient excess to remove water vapor from the reaction vessel as fast as it is formed, and when the formation of dihydrodypnone has reached a maximum, reducing the temperature

to 70 to 100° C., continuing the introduction of hydrogen, and isolating dihydrodypnol from the reaction products.

9. A process for the production of hydrogenation derivatives of dypnone from acetophenone which comprises heating at approximately atmospheric pressure the acetophenone at a temperature of 160 to 250° C. in the presence of a finely-divided nickel catalyst, introducing hydrogen in sufficient excess to remove water vapor from the reaction vessel as fast as it is formed, isolating the dihydrodypnone from the reaction products, treating it with hydrogen at superatmospheric pressure at 70 to 100° C., and separating dihydrodypnol from the reaction products.

10. A process for the production of hydrogenation derivatives of dypnone from acetophenone which comprises heating at approximately atmospheric pressure the acetophenone at a temperature of 160 to 250° C. in the presence of a finely-divided nickel catalyst, introducing hydrogen in sufficient excess to remove water vapor from the reaction vessel as fast as it is formed, isolating dihydrodypnone from the reaction products, submitting the dihydrodypnone to reduction with an aluminum alkoxide in the presence of a monohydric alcohol and separating dihydrodypnol from the reaction products.

11. A modification of the process as claimed in claim 4, wherein the acetophenone is heated in the presence of the catalyst without the introduction of hydrogen, wherein the dypnone thus produced is then submitted to hydrogenation.
